US0D1107820S

(12) **United States Design Patent** (10) **Patent No.:** **US D1,107,820 S**
(45) **Date of Patent:** ** *Dec. 30, 2025

(54) **MODEL VEHICLE BODY**

(71) Applicant: **TRAXXAS, L.P.**, McKinney, TX (US)

(72) Inventors: **Skylar Hagler**, Anna, TX (US); **Jaime Felix Barajas**, Dallas, TX (US); **Jory Sprowl**, Honey Grove, TX (US); **Casey Christen Jens Christensen**, McKinney, TX (US); **Otto Karl Allmendinger**, Rowlett, TX (US); **Adam Cole Ewing**, McKinney, TX (US); **Kent Poteet**, Lucas, TX (US)

(73) Assignee: **TRAXXAS, L.P.**, McKinney, TX (US)

(*) Notice: This patent is subject to a terminal disclaimer.

(**) Term: **15 Years**

(21) Appl. No.: **29/881,282**

(22) Filed: **Dec. 29, 2022**

(51) **LOC (15) Cl.** **21-01**

(52) **U.S. Cl.**

USPC **D21/562**; D21/561; D21/533

(58) **Field of Classification Search**

(57) **CLAIM**

The ornamental design for a model vehicle body as shown and described.

DESCRIPTION

FIG. 1 is an upper, left, front perspective view of a model vehicle body showing our new design;

FIG. 2 is an upper, right, rear perspective view thereof;

FIG. 3 is a lower, right, rear perspective view thereof;

FIG. 4 is a lower, left, front perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is an upper plan view thereof; and,

FIG. 10 is a lower plan view of the model vehicle body.

In the drawings, the broken lines illustrate portions of the model vehicle body that form no part of the claimed design.

1 Claim, 9 Drawing Sheets
